UNITED STATES PATENT OFFICE.

FRANK VOGELZANG, OF CHATSWORTH, IOWA, ASSIGNOR OF ONE-FOURTH TO MORRIS BODIN AND ONE-FOURTH TO BEN APLESON, BOTH OF CHATSWORTH, IOWA.

RAIL-CROSSING SIGNAL.

Application filed May 7, 1927. Serial No. 189,570.

My invention relates to crossing signals and it is my object to provide a device of simple, durable, and inexpensive construction for warning motorists and pedestrians of the approach toward a crossing of a train, street car or the like.

A further object of my invention is to provide a device actuated at a distance from the crossing by mechanical means.

More particularly my invention resides in a device which employs a resilient connection between the signal semaphore arm and a trip lever located at a distance near a rail of the track whereby a quick blow imparted to the lever will be transmitted more slowly to the semaphore arm.

A further object of the invention is to provide means for retaining the power of the quick blow during the time that the semaphore arm is moving upwardly.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Fig. 1 is a perspective view of my invention installed at a crossing, portions being broken away to better illustrate the construction.

Fig. 2 is a detail, sectional view on the line 2—2 of Fig. 1.

Fig. 3 is a detail, longitudinal, sectional view through the spring tension-adjusting device.

Fig. 4 is a vertical, sectional view through the top of the semaphore post, the parts being viewed in a direction substantially opposite to that of Fig. 1.

Fig. 5 is a detail, sectional view taken on the line 5—5 of Fig. 1.

Fig. 6 is a horizontal, sectional view through a portion of the mechanism shown in Fig. 5.

Fig. 7 is an elevation of one of the trip levers secured to the ties of the track, a portion of the casing, thereof, being shown in section.

Fig. 8 is a detail, sectional view taken on the line 8—8 of Fig. 7.

Fig. 9 is an elevation of the trouble signal.

I have used the reference character 10 to 55 indicate generally the highway crossed by a railway track comprising the ties 11 and the right and left rails 12 and 13, (when the track is viewed in the direction as in Fig. 1).

A semaphore post 14 is mounted at a distance from the track and near the side of the highway and at its upper end carries a casing 15, in which is journaled a shaft 16, which extends outwardly through the casing and has secured to its outer end a sema- 60 phone arm 17.

The semaphore arm 17 has a red warning disc 18 at one end and its shorter end is curved as at 19 and provided with a weight 20. It may now be noted that as the arm 70 is swung upwardly to its signalling position 21 in the direction indicated by the arrow 22, that the weight 20 will oppose this upward swinging until the arm has reached a position approximately of 45° and from 75 that point the weight 20 will aid the upward swinging of the semaphore arm. The object of thus arranging the weight 20 is to provide means for maintaining the sema-

phone arm in a vertical, depending position 80 against the action of the wind or any accidental displacement from this position and to help maintain the arm in its horizontally extended position 21 so that the mechanism, which will later be described, for raising 85 the arm will be partially relieved of the weight of the arm during the time that it remains in horizontal position. Since this mechanism includes a resilient spring, it is important that the spring be relieved of 90

tension as much as possible. A pin 23 acts as a stop for the semaphore arm in depending position and a pin 24 similarly acts as a stop for the semaphore in extended position. 95

I will now describe the operating mechanism.

Within the casing 15, an arm 25 is secured to the shaft 16 and secured to the end of the arm 25 is a spring 26, which extends down- 100

wardly through a hollow tubular casing 27. The casing 27, (Fig. 2), is secured to the post 14 by means of a band 28 which has a hinged portion 29 encircling the casing 27. The hinged portion 29 serves not only to secure the casing to the post but also as a cover for an opening 30 in the casing 27 which gives access to a tension-adjusting device shown in Fig. 3.

10 The tension-adjusting device comprises a threaded rod 31, suspended from the spring 26 and a threaded sleeve 32 which receives the rod 31. A cable 33 is swivelly connected with the lower end of the sleeve 32 and extends downwardly through the casing 27 around a pulley 34, (Fig. 5), which is enclosed by an elbow casing 35, joining the casing 27 with a horizontal tubular casing 36.

Power to raise the semaphore arm is applied to the cable 33 through the medium of a latching device which catches and retains the pull transmitted to it by first distending the spring 26 and then latching to prevent the spring contracting upwardly, whereby the contractile power of the spring will be transmitted onto the arm 25 to raise the semaphore. Thus the inertia of the semaphore arm will be overcome slowly and much less power will be required and there will be little likelihood of breakage occurring in the power transmitting mechanism. The latching device is housed within a casing 37, which is secured between a pair of ties 11 by means of ears 38 and which is provided with a cover 39 hinged to the casing 37 as at 40. Within the casing a pawl 41, which is formed as an elongated block provided with teeth 42, slides between a pair of guides 43 projecting inwardly from the sides of the casing 37. The cable 33 is secured to the pawl 41 through the medium of a block 44, pivoted to the pawl and a cable 45 is secured in the other end of the block and extends toward the other end of the casing and thence around a pulley 46. A similar cable 47 is secured to the pawl by means of a pivoted block 48. The cables 45 and 47 extend through casings 50 and 51 to remote points on either side of the highway 10 where they are connected to trip levers situated adjacent the rails of the track to be struck by a projection carried by a locomotive or the like.

It may now be noted that when either cable 45 or 47 is moved by the passing of a train, 45 that the movement will be transmitted to the cable 33 and thence to the spring 26. Since the ordinary rate of travel of a train is very fast, this movement will constitute a quick jerk; the cables used for transmitting this 50 jerk are consequently made very strong and housed within casings which may be filled with lubricant in order to reduce friction. There will be some inertia in the cables themselves, but, by making the parts strong enough, the danger of breakage, due to such

inertia, may be eliminated. The inertia of the semaphore arm, however, will be much greater than the inertia of the cables to be pulled lengthwise and consequently I employ a spring for storing the power created by the jerking of the cables. In order to retain the spring under tension until the arm has moved upwardly, the pawl 41 is provided and is adapted to engage the projection 52, which is preferably formed at the end of a hardened steel plate 53 secured to the casing 37. The pull upon the cable 45 or 47 will move the pawl 41 to a point where the teeth 42 will engage the projection 52 and the pawl will thereby retain the cable 33 while the distended spring transmits the movement to the semaphore arm.

In order to release the pawl and allow the arm to return to its normal position, I provide a release trigger 54, hinged at 55 to the casing 37, and having the flat, upper surface 56, against which the pawl may ride. The swinging end of the trigger 54 is positioned closely adjacent the projection 52 and serves to lift the pawl sufficiently to disengage the teeth 42 from the projection. In order to swing the free end of the trigger upwardly, I provide cables 57 and 58, respectively, which are together connected to the trigger through the medium of a spring 59, the former extending in one direction and the latter extending in the other direction to two trip levers 60 and 61, respectively. The cable 57 extends across the track between a pair of ties and through the housing 62 to a pulley 63 which is journaled within the elbow housing 64 and thence to the trip lever 60 while the cable 58 extends around a pulley 64, which may be housed within an extension 65 of the casing 37 and thence to the trip lever 61.

In similar manner the main operating cable 47 extends across the track through the housing 51, around a pulley in a housing 66, and thence along the track on the other side, thereof, through a housing 69, while the cable 45 extends directly up the track in the opposite direction through the housing 50, as already described.

The housing 37 is widened as at 37^a, to allow one of the cables 57 or 58 to slack laterally when the other cable is pulled.

It will now be seen that the trip levers for operating the raising cables and the release cables, respectively, are provided in pairs, positioned on opposite sides of the post 14 and on opposite sides of the track. Consequently a single projection 70, (Fig. 7), may be used, positioned on one side of the locomotive or the like and when the locomotive is approaching from one direction, the projection 70 will first engage the remote trip lever for raising the arm and then engage the release trip lever on the same side of the track for releasing the arm. The force of gravity will pull the signal arm to 125

its normal position shown in full lines in Fig. 4 when the release trip lever is actuated. When the train is approaching from the other direction, the other set of levers will be actuated.

The trip lever in each instance comprises a lever casing 71, formed integrally with a pulley casing 72. The lever housing 71 is triangular in shape so as to allow the lever 73, which is pivoted at 74 in the lower portion of the housing, to move from the position shown to an inclined position where the projection 70 may pass over the upper end of the lever. Covers 75 and 75^a are hinged to the lever. The covers prevent dirt from accumulating within the lever housing. As the lever slides forwardly, the covers slide also. The lever is formed in two sections, the upper section 73^a being hinged at 76 to the lower section 73, and a finger 77, formed integrally with the upper section 73^a, projects below the hinge to prevent movement of the section 73^a beyond the aligned position relative to the lower section shown in Fig. 7. A spring 78 serves to maintain the sections in these relative positions, being connected to the fingers 77 and to the lower section 73 as shown. Should the lever accidentally be engaged by an object moving in the direction opposite to the arrow 78, in which the projection 70 will always move when engaging the lever, the upper section 73^a will hinge rearwardly without moving the lower section.

The cable, (assuming it to be the cable 45), passes around a pulley 81 within the pulley casing 72, thence around a pulley 82 and thence around a pulley 83, which is inclined to bring the cable to the plane of the lever casing, (see Fig. 8). Thus the wear of the cable is divided among three pulleys. After passing around the pulley 83, the cable is attached to the lever.

It will be noted that there are three teeth shown on the pawl 41. Should the first tooth, which ordinarily acts, wear to such an extent that it will slip and allow the second tooth to engage, the inclination of the semaphore arm will be slightly below horizontal and this will apprise the inspector of the fact that the parts are worn so as to need repair. If the arm is horizontal, it indicates that the parts are in good condition.

Should a break occur in either of the cables 45 or 47 in such a manner as to make it impossible for the pawl 41 to be actuated when a train passes by, the raising of the trigger 54 will cause a pin 84, (Figs. 5 and 7), to engage a projecting lip 85 on a lever 86, which is pivoted at 87 within the casing 37 and which, at its other end, is fastened to a cable 88 extending upwardly around a pulley 88^a, thence forwardly through a casing 88^b, thence around a pulley in an elbow casing 88^c, and thence upwardly through a cas-

ing 88^d to a safety signal comprising a lever arm 89, pivoted at 90 to the post 14 and carrying a pawl 91 engaging a sector 92. The raising of the trigger 54 will raise the end of the pawl 41, the pin 84 raising the short end of the lever 86, the other end of the lever moving downwardly to pull the cable 88 downwardly and thereby raise the arm 89.

Ordinarily the sliding of the pawl 41 forwardly will bring the pin 84 to a position where, when the trigger raises the pin, it will not engage the lip 85.

In addition to the warning given by the semaphore arm, I provide a warning bell 90, mounted within the casing 15, actuated by a source of current, which is not shown, the circuit being made and broken by a switch point 91 on the lever 25, engaging a brush 92 for grounding the bell circuit when the semaphore arm is raised. The spring 26 serves not only to allow slow movement of the semaphore arm to its raised position, but also to keep the transmitting cable taut at all times. This is important since any slack in the cable would cause a jerk, tending to break it under the strain imposed by the quick blow of a passing train.

Some changes may be made in the construction and arrangement of the parts of my invention without departing from the real spirit and purpose of my invention, and it is my intention to cover by my claims, any modified forms of structure or use of mechanical equivalents, which may be reasonably included within their scope.

I claim as my invention:

1. In a crossing signal, a semaphore arm to be raised and means for raising said arm including a trip lever positioned at a remote point beside a rail of the crossing track, means for transmitting a movement of said trip lever to the semaphore arm including a resilient link interposed between the trip lever and the semaphore arm, and a latching device interposed between the resilient link and the trip arm for temporarily retaining the resilient link under distension immediately after it has been acted upon by the movement of the trip lever.

2. In a crossing signal, a semaphore arm to be actuated and means for actuating said arm including a trip lever adapted to receive a quick impulse from a passing object, an element connecting said trip lever with the semaphore arm, a resilient member interposed between said element and the semaphore arm, a pawl device interposed between said resilient member and the trip lever for retaining the force of the impact against the trip lever, a second trip lever and a device operated by the second trip lever for releasing the pawl.

3. In a crossing signal, a semaphore arm to be actuated and means for actuating said arm including a trip lever adapted to receive

a quick impulse from a passing object, an element connecting said trip lever with the semaphore arm, a resilient member interposed between said element and the semaphore arm, a pawl device interposed between said resilient member and the trip lever for retaining the force of the impact against the trip lever, a second trip lever and a device

operated by the second trip lever for releasing the pawl, and means actuated by said release device, should the pawl fail to respond to the impulse of the first trip lever for operating an auxiliary signal device.

Signed this 2nd day of May, 1927, in the county of Woodbury and State of Iowa.

FRANK VOGELZANG.
